(57) **CLAIM**

We claim the ornamental design for an animal leash, as shown and described.

DESCRIPTION

FIG. 1 is a perspective view of an animal leash showing our new design;

FIG. 2 is a top plan view thereof, the top and bottom sides being identical mirror images; and,

FIG. 3 is a side elevational view thereof, the left and right sides being identical mirror images.

The portions of the leash shown broken away are to indicate indeterminate length.

The broken lines showing a clip on the end of the leash are for illustrative purposes only and form no part of the claimed design.
